[57] ABSTRACT

Apparatus for thermal vapor coating an article comprises a pair of spaced fixed diaphragms and a disc having inclined channels along its periphery rotating between said fixed diaphragms for defining the steam jet impinging on the article mounted in a vacuum chamber. The inclination of the channels is such that the direct path of the jet stream between the vaporization source and the article is blocked. The rotational speed of the disc is determined as a function of the angular inclination of the channels as well as the variable velocity of the steam jets.

APPARATUS FOR THERMAL VAPOR COATING
AN ARTICLE

This invention relates to thermal vapor coating and in particular to apparatus whereby such processes can be carried out and wherein structure is provided to separate the radiation emitted from a thermal vaporization source and the steam jet.

Austrian Pat. No. 231,530 describes a process for carrying out a method of thermal vapor coating with a lower thermal load on the support material that is to be vapor coated. The essence of such a process resides in the fact that the heat radiation emanating from a thermal vaporization source is separated from the jets of steam because of its greater dimensional speed. The aforementioned patent also describes apparatus for carrying out the vapor coating process.

In general, apparatus for thermal vapor coating comprise a rotating hollow cylinder having slots on its peripheral surface and the cylinder is mounted relative to the thermal vaporization source and is rotated at such a speed so that the separation of the heat radiation from the corpuscular radiation will be achieved for the above mentioned purpose. Further, other apparatus are known which comprise the system of rotating discs and oscillating diaphragm slides.

Austrian Pat. No. 293,814, which also discloses apparatus for carrying out thermal vapor coating processes, discloses an arrangement in which the diaphragm slots follow each other in a known manner along the direction of the rotational axis of the system and wherein the diaphragm elements comprise a multiplicity of channels for the passage of steam. The channels are formed along the generatrix of a cylinder around a common axis which is inclined relative to the steam jet at such an angle that a direct passage in the direction of the jets is obstructed.

Such a system has a serious disadvantage in that it requires a very high r.p.m., in the order of approximately 50,000 r.p.m., which causes problems for the associated vacuum arrangement. However, it should be noted that the required r.p.m., within wide limits, is merely a function of the size of the surface that is to be vapor coated and thus such a disadvantage applies to all of the known prior art thermal vapor coating systems.

A thermal vapor coating system must take into consideration, among other matters, the substrate that is to be vapor coated and that normally the substrate is mounted perpendicularly above the source of the vaporization. Consequently, in small installations as are quite often used, especially in the case of electron microscopy, only a limited space is available for the mounting of the necessary components of the system.

The method and apparatus in accordance with this invention take into consideration all of the above factors. One of its advantages over the known arrangement is that it requires considerably less space and therefore the apparatus cannot only be installed in customarily used treatment installations, but enables the vaporization source to be moved in closer proximity to the substrate as is likewise frequently necessary. The last mentioned consideration also requires that the height of the rotating cylinder be kept as low as possible. This consideration, in turn, requires a stronger slant or angularization of the rotating diaphragm relative to its rotational axis. Such a large angle, however,

cannot be realized by merely inclining the axis in those cases where the slots are parallel to the axis.

Further, the invention has the advantage that it makes possible coating processes in a high vacuum with reduced thermal load of the substrate, whereby the structure has a very low height — based on the special construction of its diaphragm system — and can also otherwise be inserted directly into customary preparation installations.

10 The arrangement, according to the invention, is characterized in that the inlet and outlet slits of the diaphragm system are developed in a manner known per se, that is, as screw surfaces around the rotational axis of the diaphragm system; however, the optical direct 15 vision in the direction of the rays of steam is interdicted.

A primary object of the present invention is to provide improved thermal vapor coating apparatus which enables a considerable reduction in the size of the coating apparatus.

Another object of the invention is to provide an apparatus of the type specified in which the source of vaporization may be closely adjacent to the substrate to be coated.

25 25 A further object of the invention is to provide an improved apparatus of the type specified in which the rotational speed of the cylinder is considerably reduced.

The above, as well as other, objects and advantages will be apparent from the following description taken 30 in conjunction with the drawings wherein:

FIG. 1 is a sectional view illustrating the essential components of the apparatus which are connected to a pump system for creating a high vacuum;

FIG. 2 shows a cross-section view the rotating and 35 fixed diaphragm members of the apparatus; and

FIG. 3 shows an elevational view of a portion of the rotating and fixed diaphragm members of the apparatus.

The steam jets 9 emitted from vaporization source 1 40 are reduced by fixed diaphragms 2, 4 to the required cross section or size of the suspended element 5. Between fixed diaphragms 2, 4, cylinder 3 is mounted to rotate about a vertical axis and includes channels 8 along its periphery. The geometry of the channels is selected so that in the area of the reduced steam jet there is no direct line of sight between vaporization source 1 and the suspended element 5. Channels 8 are in the form of helical surfaces having a helix angle α (as illustrated in FIG. 2) with the transverse axis of cylinder 3. 45 Thus, channels 8 are helical which provide passages for steam jets 9. Cylinder 3 and its associated channels 8 thus form a rotating diaphragm between fixed diaphragms 2, 4.

50 The material to be coated represented by numeral 5 is suspended within vacuum chamber 6 in alignment with the slits in fixed diaphragms 2 and 4. Motor 7 is provided to rotate cylinder 3. The entire apparatus illustrated in FIG. 1 is connected to a pump system for creating a high vacuum within chamber 6.

55 The peripheral speed V of channels 8 is a function of the angle α as well as variable velocity c of the steam jets. Angle α is in turn a function of the values b , B , s , d and h of the optical impermeability of the channels. The cross-section of the vapor spray and thus the area 60 to be evaporation-coated is defined by the magnitudes of B , b , S . B and b may be varied as required but only in such a manner that the relation

$$\operatorname{tg} \alpha = (B + b + 2d)/2h$$

is fulfilled.

If no light should enter into the defined area, the separation of the channels must be:

$$s = [(B - b)/2] + 2d$$

A smaller separation s would provide an unnecessary number of channels while a greater value of s would allow the light to enter into the defined area.

It will be recognized that the following formulas apply to the apparatus of FIG. 1:

1. Tangent $\alpha = V/c$

2. From the above formula, $V = \bar{c} \cdot \operatorname{tg} \alpha$

3. The r.p.m. of the cylinder is $n = (60/\pi) \cdot (V/D)$

Assuming that D equals 0.2 m and $\alpha = 15^\circ$, then formula 3 indicates that $n = 60/\pi \cdot V/D$ which equals $(60/\pi) \cdot (\bar{c} \operatorname{tg} \alpha/D)$ which equals $25 \cdot \bar{c}$. From the above relationship and the fact that the steam jets have velocities of between 100 and 1,000 M/s, the r.p.m. of the cylinder or rotating diaphragm will be from between 2,500 and 25,000 revolutions per minute. Such R.p.ms. are easily realizable with state-of-the-art equipment even in high vacuums.

The symbols used in FIG. 2 and the above formulas are defined as follows:

V = peripheral speed of cylinder 3

$\bar{c}$ = average velocity of the steam jet

D = cylinder diameter

n = r.p.m. of the cylinder

α = angle of channels 8

d = separation of channels

b = width of slit opening in fixed diaphragm 2

B = width of slit opening in fixed diaphragm 4

s = opening of the channels

h = height of the cylinder

S = depth of the channels

What is claimed is:

1. Apparatus for thermal vapor coating an article, comprising:

a vaporization source for generating jets of steam including the coating substance;

a vacuum chamber for mounting said article; and means mounted between said vacuum chamber and said source for directing said vapor to said article, said means including a rotating disc having a number of channels along its periphery, said channels being inclined with respect to the longitudinal axis of said disc and said disc being mounted to rotate so that said channels are positioned in the jet stream between said source and said article and inclined at an angle to block the direct path of said jet stream from said source to said article.

2. Apparatus as in claim 1 wherein said means for directing said vapor to said article further include a pair of spaced diaphragms each having an aperture for passage of said jet stream and said rotating disc is mounted to pass between said spaced diaphragms.

3. Apparatus as in claim 2 wherein the rotational velocity of said disc is a function of the variable velocity of said steam jets and the angle of said channels with respect to the transverse axis of said disc.

30 4. Apparatus as in claim 3 wherein the rotational velocity of said disc is approximately 25 times the velocity of said steam jets.
